UNITED STATES PATENT OFFICE

HENRY K. MEEKS AND GEORGE O. MEEKS, OF SPOKANE, WASHINGTON

ELECTRIC CONDUIT SECTIONAL OUTLET BOX

Application filed May 28, 1930. Serial No. 455,623.

Our invention relates to electric conduit sectional outlet boxes and certain objects of the invention are to provide an outlet box comprising one or more open end units with offset overlapping lugs at their top corners and at their slanting bottom portions whereby said units may be secured together in abutting and aligned position. Further objects of the invention are to provide end plates having hinge joints and tongues adapted to be connected to said offset lugs. Still further objects are to dispose the lugs and other connecting members on the inside of the box units whereby they will not be an obstruction when installing the device. Other important objects of the invention are to provide an outlet box that may be readily assembled in any size and capacity to suit the particular local conditions, which may be readily installed within a wall, and which may be quickly disjointed and removed from the wall without damage to the device or to the wall.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a view in perspective showing an outlet box comprising only one unit and having a perforated plate secured thereto whereby the box may be secured to a wall studding or the like;

Fig. 2 is a view in perspective showing a box made of two units;

Fig. 3 is a fragmentary plan view showing the offset overlapping top lugs and the pintle screw for uniting the box units;

Fig. 4 is a fragmentary view in vertical section showing the overlapping lugs and pintle screw connection for the bottom portion of the box units;

Fig. 5 is a fragmentary detail view in elevation of said lugs;

Fig. 6 is a detail view in perspective of one of the end plates;

Fig. 7 is a view in perspective showing a single box unit;

Fig. 8 is a view in transverse vertical section taken substantially on a broken line 8, 8 of Fig. 2 and showing the connection of two box units;

Fig. 9 is a view in end elevation of the box;

Fig. 10 is a fragmentary view in horizontal section taken on a broken line 10, 10 of Fig. 9 and showing a corner connection of an end plate;

Fig. 11 is a fragmentary view in vertical section taken on a broken line 11, 11 of Fig. 2 and showing a tongue locking detail for the upper portion of an end plate; and

Fig. 12 is a similar view taken on a broken line 12, 12 of Fig. 2 and showing another locking detail for the lower portion of an end plate.

Referring to the drawings throughout which like reference numerals designate like parts, each corresponding unit of the box comprises a flat bottom portion 5, upwardly and outwardly slanting corner bottom portions 6 and upright side walls 7. Each of said side walls is provided with a lug 8 projecting outwardly from its central top edge whereby same may be secured to a wall stud or the like. Two of the diagonally opposite corners of the top edges of said upright walls are integrally provided with inwardly projecting lugs 9 which have depending fingers 10 and the other two diagonally opposite corners are provided with inwardly projecting lugs 11 which are disposed below the first-named diagonally arranged lugs a distance equal to their thicknesses or to the thickness of the upstanding walls from which said lugs are formed.

Vertically below each of the lugs 9 and at points where the slanting bottom portions 6 of the box units join the upright side walls 7 a lug 12 is formed by cutting inwardly and downwardly a portion of said bottom from the edge thereof and slightly bending said portion downwardly or outwardly. Vertically below each of the lugs 11 and at points corresponding with the lugs 12 a lug 13 is formed by cutting inwardly and upwardly

- a portion of the slanting bottom portion 6 and bending said cut portion upwardly or inwardly in conformity with the bending of the aforesaid lug 12.
- 5 The lugs 12 and 13 project outwardly from the ends 14 of the box units or are offset therefrom a corresponding distance and are provided with slots 15 whose centers are aligned with the ends of said box units.
- 10 Thus the lugs of different box units being oppositely offset and bent or deflected will overlap each other with their slots in alignment, as shown in Fig. 4, when the abutting ends of said units are placed together. The 70
- 15 lugs 9 and 11 are correspondingly offset an equal distance whereby they too will overlap when said box units are disposed in abutment and said lugs are provided with threaded holes 16 which will register one with the 75 other in the overlapped position.
- 20 In the abutting position of two box units with the lugs 9 overlapping the lugs 11 and the lugs 13 overlapping the lugs 12 and with the slots 15 in registration and the holes 16 80
- 25 also in registration, a pintle 17 is inserted through said holes and slots with its short head end screw portion 18 threaded into said holes and in this position the depending fingers 10 of the lugs 9 will engage against 85
- 30 the edges of the lugs 11 thus completing the connection between two of the box units. It will also be noted that the top edges of the 90 side walls 7 will be in alignment or in the same horizontal plane due to the fact that
- 35 the lugs 11 are disposed below the lugs 9 a distance equal to their thicknesses. It will thus be seen that a strong connection is made 95 between said box units and as many units may be likewise connected as desired.
- 40 End plates, designated as a whole by the numeral 19 and as shown in detail in Fig. 6, are adapted to be secured to the open ends of the box units. One side of said plates is provided with a hinge joint 20 and its slanting bottom edge portion is cut away, as at 21, to receive one of the lugs 13. When this side portion is installed in place to an end of a box unit said hinge will be in vertical alignment with said lug 13 and with the hole 16 in 100
- 45 one of the lugs 11. A pintle 22, corresponding 105 in all respects with the pintles 17, is installed through said hinge joint and lugs to detachably retain this portion of the end plate in place.
- 50 The other side of the end plate 19 is cut away at its slanting bottom edge, as at 23, and a tongue 24 is provided on the edge at this cut-away portion that is adapted to fit 110 into the slot 15 of one of the lugs 12 as shown
- 55 in detail in Fig. 12. The top edge portion 115 on this side of said end plate is also cut away, as at 25, to receive one of the lugs 9 and a tongue 26 is provided at said cut-away portion that fits into the hole 16 of said lug, as 120
- 60 shown in detail in Fig. 11, thus completing
- 65 the means for securing said end plate to a box unit.
- In installing an end plate 19 on the open end of a box unit the tongues 24 and 26 are first inserted into the slot 15 and hole 16 respectively after which the hinge joint portion 20 on the other side is swung into place and the pintle 22 is then inserted as will be understood. Said end plates are interchangeable and may be installed on either 75 open end of the box units. An outlet box may comprise only one box unit as shown in Fig. 1, two of said units as shown in Fig. 2, or as many units as desired and with an end plate installed on both open ends of the box 80 as a whole.
- The end plates 19 and the slanting bottom corner portions 6 of the box units are provided with the usual entries 27 for the electric 85 conduits or wires. Said end plates may be provided with channel bars secured thereto in any suitable manner that are adapted to receive the laths of a wall when installed and holes 29 may be provided in the flanges of 90 said bars for nails or other fastenings. The bottom flange of said bars may be cut away and the top flange seated on the laths when setting the box in an old wall. As shown in Fig. 1, a perforated bracket plate 30 may be secured to one of the end plates whereby 95 the device may be secured to the wall studing of a building.
- It will now be apparent that we have provided an outlet box consisting of a plurality 100 of units having overlapping lugs at their upper corners and slanting bottom portions that are adapted for the dual purpose of connecting a number of the box units together or for the purpose of securing end plates thereto. We have also provided end plates with novel 105 means whereby they may be readily secured to and disconnected from said box units, thus providing as a whole a box which may be readily assembled and installed and which may also be readily disjointed and removed. In removing the box from a wall the front 110 screws and pintles are first removed when the units may be disconnected or the end plates removed after which the units may be pulled out from the wall. Above all else it will be understood that the most useful feature of our device resides in the long pintles or bolts 17 and 22 extending from the front to the rear 115 of the boxes. Although a box may be almost entirely imbedded in a wall the heads of these pintles or bolts are always accessible and with a screwdriver said pintles may be readily removed and the box dismantled and removed without cutting or damaging the wall. Thus another section may be added for another outlet and after enlarging the recess in the wall the entire box with the added section 120 may be installed. This feature, whereby a box may be removed and another section 130

added without damage to the wall, is of prime importance in our invention.

Having thus described our invention, it being understood that minor changes in its construction and arrangement may be resorted to without departing from the scope and spirit of the invention, what we claim and desire to secure by Letters Patent of the United States is:—

- 10 1. An electric conduit sectional outlet box having in combination one or more open end box units, offset lugs for the front and bottom corners of said units adapted to overlap each other when the units are disposed in abutting relation long pintles extending from the front to the rear of said units through said lugs, and end plates for said units.
- 15 2. An electric conduit sectional outlet box having in combination one or more open end box units comprising slanting corner rear portions and upright side walls, inwardly projecting offset lugs for the front corners of said walls, offset lugs for the slanting corner rear portions of the units disposed in alignment with said front corner lugs, said front and rear lugs arranged to overlap the lugs of adjoining units when disposed in abutting relation long pintles extending from the front to the rear of said units through said lugs, and end plates for said box units.
- 20 3. An electric conduit sectional outlet box having in combination a plurality of open end box units comprising slanting corner rear portions and upright side walls, inwardly projecting offset lugs for the front corners of said walls, offset lugs for the slanting corner rear portions of the units disposed in alignment with said front corner lugs, the corresponding top and rear lugs of adjoining box units arranged to overlap each other when said units are disposed in aligned abutting relation, pintles arranged to detachably connect the aligned lugs and extending from the front to the rear of the box units, end
- 25 4. plates for the open ends of said box units, said plates having a hinge joint on one side edge adapted to register with the two disposed lugs, and a pair of tongues for the opposite side edge of the end plate arranged to fit into the other two aligned lugs.
- 30 5. In testimony whereof I affix my signature.

HENRY K. MEEKS,
GEORGE O. MEEKS.
